UNITED STATES PATENT OFFICE.

MITA MICHAJLOV, OF NEW YORK, N. Y.

ARTIFICIAL LIMB.

1,281,191.

Specification of Letters-Patent.

Patented Oct. 8, 1918.

Application filed January 2, 1918. Serial No. 209,853.

To all whom it may concern:

Be it known that I, MITA MICHAJLOV, a citizen of the United States, and resident of New York, in the county and State of New York, have invented certain new and useful Improvements in Artificial Limbs, of which the following is a full, clear, and exact specification.

This invention relates to artificial limbs, and has for its principal object to provide means for lengthening and shortening the limb to fit different wearers, so that a few sizes may be kept in stock, one of which may be readily adjusted to fit any individual customer.

The invention contemplates the provision of means for lengthening the limb both below and above the knee joint, whereby the individual requirements of each customer may be fully met. Another object is to conceal the sheaves for the suspension cords on the interior of the artificial limb. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a vertical section through the ankle portion of an artificial limb, showing one form of the invention adapted to be used when the limb is of minimum length.

Fig. 2 is a section on the line 2—2 of Fig. 1.

Fig. 3 is a view similar to Fig. 1 of a modified construction.

Fig. 4 is a section on the line 4—4 of Fig. 3.

Fig. 5 is a view similar to Fig. 1, showing the limb lengthened.

Fig. 6 is a detailed view of a modified form of extension device.

Fig. 7 is a side elevation of the upper portion of the artificial limb fitted with an extension device.

Fig. 8 is a section on the line 8—8 of Fig. 7, and

Fig. 9 is a section on the line 9—9 of Fig. 7.

Referring first to Figs. 1 to 5, inclusive, of the drawings, 1 designates the ankle section of an artificial limb which is divided horizontally at 2 into an upper portion 3 and lower portion 4. Said portions 3 and 4 are provided with registering dove-tailed transverse grooves 5 and 6 in their meeting faces, and are held together by locking strips 7 which are dove-tailed to fit said grooves 5 and 6. The dove-tailed strips 7 are retained in place by pins 8 passed through the limb preferably at right angles to said strips 7. These strips are further retained by the rods 9 which extend up through the bottom of the limb for connecting the foot thereto, said rods 9 being passed through the dove-tailed strips 7. Other rods 90 are connected to the rods 9 by a universal joint 91, whereby the foot 92 is swiveled to the ankle section of the limb, as illustrated in Fig. 1. As illustrated in Figs. 1 and 2, there are two of the dove-tailed strips 7 used to correspond with a U-shaped connecting rod having two upwardly extending arms or rods 9. If the artificial limb has a single rod for connecting the foot thereto, as at 10 in Figs. 3 and 4, only one of the dove-tailed strips 7 is used. Otherwise, the construction shown in Figs. 3 and 4 is the same as that illustrated in Figs. 1 and 2.

The limbs shown in Figs. 1 to 4, inclusive, may be called stock limbs because they are of the minimum length. When it is desired to lengthen the limb, an extension piece 11, Fig. 5, is substituted for the dove-tailed strips 7, and is held in place in the same manner as already described in connection with said strips. The extension piece 11 has a body portion 12 of any desired thickness, say from $\frac{1}{8}$ of an inch to several inches, which fits between and spaces apart the portions 3 and 4 of the limb. On the upper and lower faces of said body portion 12 there are dove-tailed projections 13 which fit the grooves 5 and 6 in said portions 3 and 4. It will thus be seen that by varying the thickness of the body portion 12 of the extension piece 11, the ankle portion of the limb may be lengthened to any desired extent. When the form of limb shown in Figs. 3 and 4 is used, the extension piece is provided with a single dove-tailed projection 13 on each of its upper and lower faces, as shown at 14 in Fig. 6. In Fig. 5 two

projections 13 are shown on each face of the extension piece to correspond with the construction illustrated in Figs. 1 and 2.

Referring now to Figs. 7, 8 and 9 of the drawings, 15 designates the upper end of the ankle section the lower end of which is shown in Figs. 1, 3 and 5. This portion 15 is hinged to the knee cap 16 by means of metal straps 17 riveted at 18 to the part 15, 10 and other metal straps 19 riveted at 20 to the knee cap 16, said straps 17 and 19 being swiveled together by means of a cross-pin 21. The knee cap 16 is made separate from the upper portion 22 of the limb usually 15 known as the socket member, and between said parts a lengthening or extension piece 23 of any desired thickness may be placed for increasing the length of the limb above the knee joint. The extension piece 23 and 20 socket member 22 are retained in proper relative position with respect to the knee cap 16 by the straps 19 which are preferably dove-tailed in cross section and fit in correspondingly shaped grooves 24 and 25 25 in channel pieces 26 and 27 inset in the sides of the extension piece and socket member, respectively. Said parts may be further retained in proper relative position by strips 28 secured at 29 to the inner surface of the 30 knee cap 16, as shown in Fig. 9, and fitted in grooves 30 and 31 in channel pieces 32 and 33, respectively, inset in the inner surface of the extension piece 23 and socket member 22 at diametrically opposite points 35 and between the straps 19, as illustrated in Fig. 8.

The extension piece 23 and socket member 22 are prevented from separating along the straps 19 and strips 28 by the suspension 40 cords 34 which are passed around sheaves 35 and are designed to be attached to the usual shoulder bands, not shown. The sheaves 35 are housed in cavities 36 in the knee cap below the straps 19, as shown in 45 Figs. 7 and 9, where they are out of the way and do not form lumps on the outside of the limb, as in previous constructions. It should be understood that the strips or straps used for retaining the upper portions 50 of the limb and the extension piece in proper relation may be arranged all on the outside or all on the inside, as well as part on the inside and part on the outside as shown in Fig. 8. Other detail changes may

also be made in the construction herein illustrated and described without departing from the invention.

Having thus described my invention, what I claim as new and desire to secure by Letters Patent of the United States is:—

1. The combination with an artificial limb divided transversely into two parts, each having a dove-tailed groove, of a dove-tailed connecting piece fitted in said grooves, and means for retaining said connecting piece in place.

2. The combination with an artificial limb divided transversely into two parts, having grooves in their facing surfaces, of an extension piece arranged between said parts 70 and having projections on its opposite faces to interlock with said grooves.

3. The combination with an artificial limb divided transversely into two parts of straps connected to one part and extending along 75 the other part, said other part having grooves to fit around said straps, and an extension piece arranged between the parts of the limb and also having grooves to fit around said straps.

4. The combination with an artificial limb divided transversely into two parts, of straps constituting part of the knee joint and attached to the lower part of the limb, the upper part having grooves to fit around 85 said straps, and an extension piece arranged between said parts and also having grooves to fit around said straps.

5. The combination with an artificial limb comprising upper and lower portions connected by a knee joint, the upper portion having cavities therein, of straps constituting part of the knee joint and over-lying said cavities, sheaves mounted on said straps and housed in said cavities and suspension 95 cords passed around said sheaves.

6. The combination with an artificial limb divided transversely into two parts, of an extension piece arranged between said parts, means for retaining said parts and extension piece in alinement, and suspension cords attached to the lower part for retaining said parts and extension piece in contact with each other in use.

In testimony whereof I have signed my 105 name to this specification.

MITA MICHAJLOV.
